UNITED STATES PATENT OFFICE.

HENRY E. WOOD, OF BLOOMFIELD, NEW JERSEY, ASSIGNOR TO TOWER & LYON COMPANY, OF NEW YORK, N. Y., A CORPORATION OF NEW YORK.

HANDCUFF.

No. 930,014.

Specification of Letters Patent.

Patented Aug. 3, 1909.

Application filed August 10, 1908. Serial No. 447,700.

To all whom it may concern:

Be it known that I, HENRY E. Wood, a citizen of the United States of America, and residing at Bloomfield, in the county of Essex and State of New Jersey, have invented certain new and useful Improvements in Handcuffs, of which the following is a specification, such as will enable those skilled in the art to which it appertains to make and use the same.

This invention relates to handcuffs and the object thereof is to provide a lock therefor which has three positions, an unlocked, a spring locked and a fully locked; a further object being to provide means, exterior of said lock, for manually converting said lock from its open to its spring locked position; a further object being to provide a lock which permits complete rotation of the key in producing any position thereof, thereby preventing the breakage of said key common to handcuff locks as at present constructed; a further object being to provide the manually operable means of such shape and strength as to prevent injury thereto, to make the same independent of the lock elements and thereby prevent the derangement of said elements and to so place the said means as not to be operable upon said lock elements if accidentally struck; a further object being to provide a manually operable latch tumbler which is entirely independent of the key or of the key tumblers and a still further object being to provide such a lock for handcuffs which is simple in construction and use, which cannot readily get out of order and which is well adapted to the purpose for which it is designed.

My invention is fully described in the following specification, of which the accompanying drawings form a part, in which the separate parts are designated by the same reference characters in each of the views, and in which:—

Figure 1 is a face view of a handcuff constructed according to my invention, a part thereof being broken away; Fig. 2 is a sectional view thereof, on the line 2—2 of Fig. 6, but showing all the lock elements, and in a locked state; Fig. 3 is a similar view with the key tumblers omitted to show the novel elements; Fig. 4 is a view similar to Fig. 3 but with the parts in a spring locked position; Fig. 5 is a similar view but

with the parts in an open or unlocked position; Fig. 6 is a sectional view taken on the line 6—6 of Fig. 2; and Fig. 7 is a view of one of the elements which I employ.

In the drawing forming a part of this specification, I have shown a handcuff of the usual form and comprising a radius bar a , a segment bar b provided with teeth b^2 , pivotally connected at c and provided with the usual link c^2 , said radius bar being provided with a lock socket a^2 , a cover a^3 therefor, pivots a^4 and a^5 , key post a^6 upon which the key a^7 rotates and a segmental passage a^8 for the segment or ratchet bar b .

Mounted upon the pivot a^4 is a latch d normally forced outwardly by a spring d^2 and comprising a pointed nose d^3 for engagement with the ratchet bar b and a leg d^4 similar to that shown and described in Letters Patent No. 222,751.

Mounted upon the pivot a^5 are two key tumblers e and e^2 adapted to be moved by the key a^7 and having the usual notch or recess e^3 and it will be understood that as many of these key tumblers may be employed as may be found desirable, and also mounted on the pivot a^5 is a latch tumbler f having a nose f^2 , notch f^3 adjacent thereto, dependent foot f^4 and a spring f^5 normally forcing the nose f^2 downwardly, and bearing against the foot f^4 is a pin or plunger f^6 which extends beyond the exterior of the bar a and is movable therein, is preferably made of a cylindrical form to gain strength and is entirely independent of the lock elements.

Slidably movable in the socket a^2 is a bolt h having key lugs h^2 , h^3 and h^4 , as clearly shown in Fig. 7, and being provided with an integral block h^5 at its outer end and with two projections h^6 and h^7 upon opposite sides thereof and serving as guides in the movement of said bolt by means of grooves h^8 and h^9 in the lock casing, the projection h^7 serving also as a stop in connection with the tumblers e , e^2 and f , as clearly shown.

When the parts are in the position shown in Fig. 2, and the key be rotated in the direction of the arrow, the leaf thereof raises the tumblers e and e^2 from their obstructing position adjacent the stop h^7 and, continuing, the key engages the lug h^2 of the bolt h and moves said bolt backwardly into the position shown in Fig. 4, thereby moving the block

h^5 from beneath the latch nose d^3 , and, the tumblers having been released by a full turn of the key, the notches e^8 of said tumblers engage the stop h^7 and lock the bolt in this position, permitting movement of the latch d on its pivot and thereby permitting the ratchet bar b to be forced inwardly but preventing the withdrawal thereof, this being the spring locked position of the handcuff, and if it be desired to again lock the same fully, rotation of the key in the opposite direction returns the parts to the position shown in Fig. 2 from which they had just been moved. When it is desired to open the handcuff, the key is again inserted and again rotated in the direction of the arrow and, the tumblers e and e^2 being again raised, the bolt is again moved backwardly by the engagement of the key with the lug h^3 , into the position shown in Fig. 5, thus drawing the latch d out of engagement with the ratchet bar b and, the stop h^7 having reached the position of the notch f^3 , the latch tumbler f drops and locks the bolt h in this position, this result requiring the complete rotation of the key and permitting its removal from the lock, other locks of this type requiring that a constant tension be kept upon the key in a partially rotated position in order to hold the lock open against its spring and it is because of this fact that so many keys are broken and the handcuffs made useless and it is frequently necessary to destroy the same in the removal thereof. It will be seen, by my construction, that greater strain cannot be exerted upon the key than is required to overcome the springs of the tumblers and the latch. When the handcuff is in this open or unlocked position, it may be closed and carried in the pocket without fear of its being locked and, when it is desired to place the same upon a person, it is merely slipped over the hands or closed about the wrist in the usual manner and the plunger f^6 pressed inwardly, thus raising the tumbler f out of engagement with the stop h^7 and the bolt is carried forwardly by the spring action of the latch d and the handcuff is again spring locked and may be readily adjusted to the size of the wrists of the wearer, no key being necessary for this result, and when the handcuff has been properly adjusted, the key may be inserted and rotated in a direction opposite to the arrow, the parts now being in the position shown in Fig. 4, and the bolt is shot forwardly into the position shown in Fig. 2, whereby the block h^5 is held beneath the nose d^8 and movement of the latch and of the ratchet bar prevented. It will therefore be seen that one rotation of the key carries the parts from a fully locked to a spring locked condition; another rotation carries the parts into an open position or another rotation in the opposite direction carries the parts into

their fully locked condition and, when in the open condition, no key is needed to lock the handcuff in place nor for adjusting the same to various persons.

It will be seen that I place my plunger f^6 parallel with the axial plane of the radius bar a and project the same through the lock casing at an incline to the surface thereof thereby obviating the necessity for looking or feeling for the said plunger as, with the fingers at the end of the bar a , and the hand being contracted, the thumb naturally strikes the plunger f^6 by sliding down the inclined surface of the bar a and the handcuff may be quickly locked and, because of this position of the said plunger, a blow or pressure from practically any possible direction upon the said plunger either moves it outwardly or does not move it at all and the lock elements are consequently not affected by such blow or pressure, and, because of the fact that it is independent of the lock elements, it may be made of any size, shape or strength in order to prevent injury thereto by persons attempting to open the handcuff in any other than the usual manner and, the latch tumbler f being also independent of the other lock elements and of the key, movement of the plunger cannot affect the other lock elements, and in the case of needed repairs, said plunger f is readily replaced because of its independence.

It will be evident that various changes in and modifications of the construction shown and described may be made without departing from the spirit thereof or sacrificing its advantages, and,

Having fully described my invention, what I claim as new and desire to secure by Letters Patent, is:—

1. A handcuff, comprising a radius bar, a ratchet bar, a spring latch engaging said ratchet bar, a bolt for locking said latch against movement, a key to withdraw said bolt, a tumbler to hold said bolt in a withdrawn position and means, exterior of said elements, for actuating said tumbler to release said bolt.

2. A handcuff, comprising a radius bar, a ratchet bar, and means for locking the same together, said means consisting of a spring latch engaging said ratchet bar, a key for withdrawing said latch from said bar, a tumbler for holding said latch in a withdrawn position and a device, independent of said tumbler and exterior of said locking means for releasing said latch from said tumbler.

3. A handcuff, comprising a radius bar, a ratchet bar, and means for locking the same together, said means consisting of a spring latch engaging said ratchet bar, a bolt for releasing said latch from said bar, a key for moving said bolt, a tumbler for holding said bolt in a backward position and a plunger,

independent of and exterior of said locking means for releasing said bolt from said tumbler.

4. A handcuff, comprising a radius bar, a ratchet bar, and means for locking the same together, said means consisting of a spring latch, means to lock the same against movement, means to release the same from said bar, means to hold the same in a released position and a device, independent of and exterior of said locking means for permitting said latch to resume its locking position with said ratchet bar.

5. In a handcuff comprising a radius bar, and a ratchet bar; a spring latch, a bolt for actuating the same, a key for actuating said bolt, a spring actuated tumbler for engaging said bolt in its backward position and a plunger extending outside of said radius bar for actuating said tumbler to release said bolt.

6. In a handcuff comprising a radius bar and a ratchet bar; a spring latch, a sliding

bolt adapted to engage said latch, a key for moving said bolt, a tumbler, spring actuated in one direction and manually and exteriorly actuated in the opposite direction, means thereon to engage said bolt when in a backward position to release said bar, said tumbler having a projecting nose, a nose adjacent thereto and a foot bearing against said manually actuated means.

7. In a handcuff lock, a latch, a bolt having a projection thereon for moving said latch, a key for moving said bolt, a tumbler having a notch to engage said projection and an exteriorly operable plunger for releasing said tumbler from said bolt.

In testimony that I claim the foregoing as my invention I have signed my name in presence of the subscribing witnesses this 8th day of August 1908.

HENRY E. WOOD.
